TOOL RETAINER

Earl B. Lear, Detroit, Mich., assignor to Chicago
Pneumatic Tool Company, New York, N. Y., a
corporation of New Jersey

Application April 3, 1937, Serial No. 134,716

2 Claims. (Cl. 279—19.1)

This invention relates to retainers for percussive tools and more particularly to a retainer for preventing a drill steel from becoming accidentally detached from the front head of a rock drill in which it is supported.

Among the objects of the invention are the provision of improved means for effectively holding the retainer in adjusted position; the employment of resilient means for mounting the retainer on the front head of a rock drill; and the provision of a device which is simple in construction and inexpensive to manufacture. An important feature of the invention resides in a renewable bushing seated in a non-circular socket in the side of the front head, said bushing being arranged to receive one of the trunnions which carry the retainer, and being adapted to cooperate with the trunnion to yieldingly lock the latter in adjusted position.

Other objects and features of the invention will be more clearly pointed out in the following description and appended claims.

In the accompanying drawing which illustrates one embodiment of the invention:

Fig. 1 is a front view partly in elevation and partly in section of a fragmentary portion of a rock drill embodying the invention;

Fig. 2 is a side elevation, looking from right to left in Fig. 1;

Fig. 3 is a cross section looking upwardly, as indicated by the arrows 3 in Fig. 1;

Fig. 4 is a side elevation showing a fragmentary portion of one of the bushings seated in a socket in the side of the front head;

Fig. 5 is a perspective view of the bushing shown in Fig. 4;

Fig. 6 is a side elevational view of one of the trunnions;

Fig. 7 is a front elevational view of said trunnion; and

Fig. 8 is a plan view of the trunnion.

Figs. 4 to 8 inclusive are drawn on a larger scale than Figs. 1, 2 and 3. Referring particularly to Fig. 1, a drill steel 10 is provided with a collar 11 engaging the lower end of a chuck 12 mounted in a bore 13 in the front head 14 of a rock drill. Shank 15 of the steel is of polygonal cross-section and has a sliding fit with the chuck. The upper end of the shank is adapted to receive blows delivered by a piston extension 16. The structure described up to this point is conventional.

In accordance with the present invention, the front head 14 has a pair of aligned transverse bores 18 extending inwardly from a pair of bosses

19 at opposite sides of the front head. Each bore 18 provides a socket for receiving a trunnion bushing 20. The bushing has a hollow stem 21 which fits the bore 18 and a flange 22 which seats against a flat surface on boss 19. The bushings 20 are held in their respective sockets by a press fit and are adapted to be removed and replaced after they have become worn. In order to prevent the bushing from turning, flanges 22 are provided with non-circular or flattened portions 22a adapted to seat on lugs 23 projecting from and integral with the front head.

The bushings 20 support a pair of trunnions 24. As shown in Figs. 6, 7 and 8, each trunnion has a pivot portion 25 and a head 26, the head having a bore 27. The pivots 25 are mounted to turn in bores 28 in the bushings. The heads 26 are yieldingly held, by means to be described presently, in engagement with the outer faces of the flanges 22 on the bushings. As shown in Figs. 6 and 7, the abutting face of the head 26 is generally flat but is provided with radially extending grooves 29. These grooves cooperate with ribs or projections 30 on the outside face of the bushing flange 22. In the illustrative embodiment of the invention, there are three sets of grooves on each trunnion, any one set of which may register with the bushing ribs and thereby yieldingly lock the trunnions in any one of three different positions of adjustment.

A resilient tool retainer 32 has a yoke portion 33 of ordinary construction adapted to underlie the collar 11 on the drill steel 10 and a pair of upstanding substantially parallel arms 34. The arms 34 have cylindrical extensions 35 slidably fitting the trunnion bores 27 and have collars 36 seating against the lower ends of the trunnions. The upper extremities of the arms 34 are provided with removable means such as nuts 37. Compression springs 38 surround the extensions 35 and abut against the nuts 37 to support the retainer in its uppermost position with the collars 36 seated on the trunnions. The retainer 32 is so constructed that the arms 34 are under tension when connected to the trunnions 24 and tend to force the trunnions toward each other.

In operation, the piston 16 delivers a succession of impacts to the drill steel 10 and, under certain conditions, the collar 11 of the drill steel may strike against the yoke portion 33 of the retainer 32. Springs 38 act as a shock absorber by permitting the retainer to yield in the direction of the impacts. This minimizes wear on the front head and prolongs the life of the retainer. The retainer 32 is normally held in the position shown

in full lines in Fig. 2. When it is desired to change drill steels, the retainer is swung to the broken line position. Movement away from its adjusted position is resisted by the pressure of the grooved trunnions 24 against the projections 30 on the stationary bushings 20 caused by the resiliency of the retainer arms. As the retainer is swung, the projection 30 first cams the trunnions 24 apart, thereby increasing the tension of the retainer arms, and later permits the trunnions to snap back when a different set of grooves 29 becomes aligned with the projections 30. Preferably, though not necessarily, the construction of the bushings and trunnions is identical on both sides of the front head.

It will be apparent to those skilled in the art that various changes and adaptations of the illustrative embodiment of the invention may be resorted to without departing from the spirit of the invention. For example, the cam arrangement between the bushings and trunnions may be reversed so that the grooves are formed on the bushings and the projections are carried by the trunnions. Furthermore, the "front head" referred to in the specification and claims need not necessarily be in one piece but may comprise several parts carried by the cylinder either in fixed relation or so connected relative thereto as to accomplish the results obtained by the illustrative embodiment of the invention.

What is claimed is:

1. A rock drill comprising a front head and a collared drill steel supported therein, a retainer having a yoke portion adapted to underlie the collar and having resilient arms extending upwardly therefrom along the sides of the front head, said front head having a pair of diametrically opposed transverse bores extending inwardly from opposite sides of the front head, each arm of the retainer being carried by a trunnion, each trunnion having a head to receive the associated retainer arm and having a pivot portion which is integral with the head and which projects into the associated bore in the front head, and means for resisting pivotal movement of the trunnions

and retainer about the trunnion axis, said means comprising a groove or depression formed on the inner face of one of the trunnion heads and extending outwardly from the pivot portion, and a complementary rib affixed to and projecting outwardly from the front head and positioned to register with said groove, said resilient retainer arms being arranged to urge said trunnions toward each other and thereby yieldingly hold the groove and rib in registry.

2. A rock drill comprising a front head and a collared drill steel supported therein, a retainer having a yoke portion normally underlying the collar and having arms extending upwardly on opposite sides of the front head, said front head having bosses on its opposite sides and having a pair of transverse bores extending inwardly from said bosses, a pair of renewable bushings mounted in said bores and held therein by a press fit, each bushing having an integral flange seated on the associated boss, a pair of axially aligned trunnions having integral pivot portions mounted to turn in said bushings and removable from the front head by movement away from each other, each bushing flange being disposed to surround the associated pivot portion, each trunnion having a longitudinal bore in line with and receiving an arm of the retainer, whereby said retainer normally prevents removal of the trunnions from the front head, said arms being shaped to fit the trunnion bores, removable members secured to the free ends of the arms, springs between said members and the trunnions, and means yieldingly resisting rocking movement of the trunnions and arms away from the normal position, said means comprising a cam surface formed on one of the trunnions and a complementary cam element formed on the outside face of the flange on the associated bushing, said retainer being resilient to force said trunnions toward each other and to hold said cam surface in engagement with said cam element, said front head, drill steel, retainer arms, trunnion bores, pivot portions and bushings all being mounted on axes in the same plane.
